UNITED STATES PATENT OFFICE.

CASSINUSS KENDALL AUSTIN, OF WOODSTOCK, ILLINOIS.

SPARK-PLUG.

1,166,108.

Specification of Letters Patent. Patented Dec. 28, 1915.

Application filed January 16, 1914. Serial No. 812,399.

To all whom it may concern:

Be it known that I, CASSINUSS KENDALL AUSTIN, a citizen of the United States, and a resident of Woodstock, in the county of McHenry and State of Illinois, have invented certain new and useful Improvements in Spark-Plugs; and I do hereby declare that the following is a full, clear, and exact description thereof, reference being had to the accompanying drawings, and to the letters of reference marked thereon, which form a part of this specification.

This invention relates to spark plugs adapted to be used for ignition purposes in connection with internal combustion engines.

The principal object of the invention is to provide a simple, economical and efficient spark plug for internal combustion engines.

A further object of the invention is to provide a spark plug comprising a plurality of conducting wires or electrodes surrounded by insulating material and adapted to enable one or more of the electrodes surrounded by insulating material to be grounded or held in contact with a metallic part at a point or points protected or covered by the insulator, so as to prevent to as great an extent as possible the accumulation of products of combustion or other undesirable substances tending to foul the plug or produce a short circuit.

A further object of the invention is to provide an insulator having a plurality of electrodes therein, all adapted to be removably mounted in a metallic part and to be readily removed and cleaned, or repaired, and replaced in an efficient manner.

Other and further objects of the invention will appear from the accompanying description and claim and from an inspection of the accompanying drawings.

The invention consists in the features, combinations of elements, and details of construction herein described and claimed.

In the accompanying drawings, Figure 1 is a view in central sectional elevation of a spark plug constructed in accordance with my invention and improvements; and Fig. 2, a similar view in central sectional elevation of another form of spark plug constructed in accordance with my invention.

In constructing a spark plug in accordance with my invention and improvements in the form shown in Fig. 1 of the drawings, I provide a core *a* of porcelain, mica, or similar non-conducting material. The core is, by preference, provided with an annular enlargement or shouldered portion *b* having, by preference, upwardly and inwardly tapered surface portions adapted to engage a similar opening *c* in a metallic bushing, sleeve or nut *d* which encircles the core and is provided with a shouldered portion *e* adapted to enable the bushing or nut to be screwed into and out of operative position. The bushing or nut *d* has suitable outer screw-threads *f* which are adapted to engage similar inner screw-threads *g* in a metallic supporting member, such as the outer or main metallic body portion *h* of the plug. The main body portion *h* of the plug has outer screw-threads *h'* adapted to enable the plug to be secured to an ignition chamber or an engine cylinder or cylinder head, and is provided with a central axial opening *i* therethrough, said axial opening having, by preference, a portion *k* of relatively large diameter adapted to admit the shouldered portion *b* of the core, the sleeve or bushing *d*, and a gasket *l*. Said gasket is formed of suitable compressible material adapted to encircle the core and form a tight joint between the insulating core and the main body of the plug *h*, and is interposed between the core and the shouldered main body portion of the plug. An aperture *m* extends longitudinally through or from end to end of the core, and in this aperture is mounted a wire or electrode *n*, formed of metal or other suitable electrically conductive material, one end *o* of which is adapted to be connected with a wire or other suitable member *y* of an electric circuit, and the opposite end *p* of which forms a sparking point which is located adjacent to a similar sparking point *q* formed by a corresponding end portion of a metallic wire or electrode *r*. The wire or electrode *r* is mounted in position to extend through a longitudinal opening *s* in the same core or insulator *a* in which the electrode *n* is mounted. The electrodes are thus insulated

from each other by the same insulator or core and are removable with the core. The opening *s* has a terminal or mouth at the periphery of the core adjacent to the inner, 5 preferably tapered, portion or surface *t* of the bushing *d*, already described. The corresponding end *u* of the wire or electrode *r* is located in the peripheral metal encircled mouth of the opening *s*, in position to engage and to be securely held in contact with the metallic tapered inner surface of the sleeve or bushing *d*, so as to form a contact or electrical connection between the wire *r* and said surrounding metallic member. The 10 end *u* and point of contact between the wire *r* or ground wire and metallic bushing *d* are thus covered and protected by the insulating material and inclosed within the metallic sleeve or bushing *d*, so that no foul matter or 15 foreign substance can reach the point of contact.

The wire *n* is, by preference, provided with a screw-threaded part or connecting member *o*, having a nut *v* in threaded engagement therewith and adapted to be held in position upon the outer end of the insulating core. A threaded thumb nut or connecting member *w* is mounted in threaded engagement with the wire *n* and is adapted 20 to securely connect a metallic wire or other suitable member *y* of an electric circuit with the wire *n*, so that the latter is embraced within an electric circuit of which the members *y* and *r* each form a part, and which 25 circuit may be of any desired or known form, comprising, or connected with, a suitable source of electric supply.

In making a spark plug of the form shown in Fig. 2, a core 2 of insulating material, such as porcelain or mica, is provided having an enlarged or annularly shouldered end portion 3. A metallic threaded encircling sleeve or bushing 4 is shrunk or sweated upon the core, and is, by preference, provided with a suitable shouldered or nut portion 5 adapted to enable the sleeve to be screwed into threaded engagement with a relatively large inner threaded portion 6 of a central aperture 7 in the main metallic 40 body portion 8 of the spark plug, so as to hold the core and the electrodes in operative position. The main metallic body 8 of the plug is provided with outer screw threads 9 adapted to enable the plug to be mounted in 45 threaded engagement with an ignition chamber, or the cylinder or cylinder head of an engine or other device in connection with which the plug is to be used. A gasket 10 of suitable compressible material is interposed between the end of the body portion 8 of the plug and the sleeve 4, preferably at a point located between the member 8 and the shoulder 3 of the core 2. A metallic wire or electric conductor 11 extends through a

suitable longitudinal or axial opening 12 in 65 the core 2 of insulating material and is provided at its outer projecting threaded end portion 13 with a metallic nut 14 secured thereto. The nut is thus adapted to be held in rigid engagement with the end of the core 70 2. A threaded nut 15 is also mounted in threaded engagement with the end portion 13 of the wire 11 and is adapted to securely hold a wire or other suitable member 16 of an electric circuit comprising wires or electrical conductors connected with a suitable source of electric supply. Any desired number of wires or electrodes 17, having projecting end portions or sparking points 18 adjacent to the end portion or sparking point 19 of the wire 11, already described, are mounted in suitable openings in the core 2 of insulating material in such position that the end 20 of each of said wires 17 extends out, by preference laterally through the peripheral portion of the core 2 at a point where the core is entirely surrounded and protected by a metallic portion such as the sleeve 4, so that each end portion 20 comes in contact with the inner surface of the metallic portion or sleeve which is in turn connected with a suitable metallic member such as the main plug member 8 adapted to form a suitable electrical conductor within the electric circuit which thus includes the insulated wires or electrodes 11 and 17 and the metallic members 4 and 8 of the plug. 90

From the foregoing it will be seen that a core of insulated material having a plurality of electrodes therein, as described, is 100 adapted to be readily removed and replaced and with it the electrodes, so that the core and electrodes can be examined and cleaned or repaired with facility. The points of contact between the electrodes which have their 105 grounded or contact ends encircled by and in contact with a metallic plug member, are removably held in position to maintain such contact, or to form an electrical connection between such electrodes and the adjacent 110 surface of such metallic member, by means of the threaded connection between the core-encircling sleeve and the corresponding plug member with which the sleeve is removably connected.

115
I claim:

A spark plug, comprising a core or wire holder made of non-conductive material, at least three wires therein, and terminating in adjacent points at one end of said holder, 120 one of said wires being longer than the other wires, and said longer wire extending substantially the full length of the holder and adapted to be connected with an electric circuit, the shorter wires extending to points 125 intermediate the ends of said holder and there being exposed, a metallic sleeve surrounding said holder and adapted to be se-

cured to the wall of an explosion chamber, and an annular metallic member inserted in and held within said sleeve, said annular member being in contact with the exposed 5 ends of said shorter wires.

In testimony, that I claim the foregoing as my invention I affix my signature in the

presence of two witnesses, this 8th day of January A. D. 1914.

CASSINUSS KENDALL AUSTIN.
